UNITED STATES PATENT OFFICE.

JOHN S. ZINK, OF TULSA, OKLAHOMA.

GAS BURNER.

Application filed July 5, 1927. Serial No. 203,473.

My invention consists in new and useful improvements in gas burners of the type adapted to be used in boilers, industrial furnaces and the like, and has for its object to 5 provide a burner simple and durable in construction, easy to install, and safe and convenient to operate.

Another object of my invention is to provide a burner economical in fuel consumption, 10 and one which, due to my particular arrangement, will not pulsate, blow out nor back fire.

A still further object of my invention is the quick and thorough mixing of air and gas at a point close to, but not in the burner.

15 With the above and other objects in view which will appear as the description proceeds, my invention consists in the novel features herein set forth, illustrated in the accompanying drawings, and more particularly 20 pointed out in the appended claims.

Referring to the drawings, in which numerals of like character designate similar parts throughout the several views,

Fig. 1 is a perspective view in side elevation, showing the assembled burner,

Fig. 2 is an end view of the same,

Fig. 3 is a transverse section of the burner,

Fig. 4 is a detail sectional view showing the air control operating means, and

30 Fig. 5 is a sectional view taken vertically through the central portion of the burner.

In the drawings, 1 represents an air tube or cylinder, open at each end, and preferably composed of cast iron. Within the tube 35 1, and near one end thereof, I provide a transversely extending yoke 2, supporting centrally thereof a cylindrical collar 3, apertured to receive a set screw 4, for the purpose herein-after set forth.

40 5 represents a gas supply pipe, which extends longitudinally through said cylinder 1, and is held in place by means of the collar 3 and set screw 4 on the yoke 2. The inner end of the supply pipe 5 is connected into a star type gas burner or distributor 6, each point or arm of which is drilled with a plurality of gas apertures arranged in concentric circles and at such an angle that each gas jet impinges with the adjacent jet of the same circle

45 50 of the neighboring point or arm of the distributor. The opposite end of the gas pipe 5 projects outwardly beyond the extremity of the cylinder 1, and is connected to the gas supply in any suitable manner.

55 7 designates a circular disk provided with a central aperture and collar 8, whereby the

same may be slidably mounted on the outer end of the pipe 5, as clearly shown in Fig. 1. The collar 8 is apertured and threaded to receive an adjusting and locking screw 9, which, 60 for convenience, extends beyond the circumference of said disk 7, and cylinder 1, being bent over to form a handle at its free end.

The use and operation of my improved gas burner are as follows.

Assuming that the parts of the burner are assembled and the device mounted in the wall of a furnace or the like, and the outer end of the pipe 5 connected to a source of gas supply, the disk 7 is adjusted on the pipe 5 to the desired position, to allow the proper volume of air to be sucked into the tube or cylinder 1 at the intake end, and the screw 9 is then tightened to secure the disk 7 in place. It will thus be seen that as the gas is discharged from 75 the apertures in the gas distributor 6, it will be thoroughly mixed with the air sucked into the cylinder 1 through the space between said cylinder and the disk 7, and due to the angularly disposed apertures in said distributor 6, 80 said mixture will take place at a point close to, but not in the cylinder 1, whereby backfiring is prevented if the flame is turned low, and the flame cannot be jerked out due to sudden changes in either draft or gas pressure.

85 From the foregoing, it is believed that my invention may be clearly understood by those skilled in the art, without further description, it being borne in mind that numerous changes 90 may be made in the details of construction, without departing from the spirit of the invention as set forth in the following claims.

What I claim and desire to secure by Letters Patent is:

95 1. A gas burner, comprising a cylindrical air tube, open at both ends, a gas supply pipe extending longitudinally through the center thereof, a gas distributor on one end of said pipe, and within said tube, having a plurality 100 of converging jets, the other end of said pipe projecting outwardly beyond said tube, and means slideable on said pipe adjacent said tube for controlling the induction of air into the tube.

105 2. A gas burner as claimed in claim 1, wherein said gas distributor is provided with a plurality of gas apertures arranged in concentric circles and at an angle to the face of the distributor, each of said apertures converging toward the adjacent aperture in the same circle, whereby the streams of gas from

the adjacent converging apertures, and the air sucked through said tube between said apertures, impinge at a point exterior of said tube.

5. 3. A gas burner as claimed in claim 1, wherein said gas distributor is provided with a plurality of gas apertures so arranged that

the streams of gas from the laterally adjacent apertures, and the air sucked through said tube between said apertures, impinge at pre-¹⁰ determined points exterior of said tube.

In testimony whereof I affix my signature.

JOHN S. ZINK.
